UNITED STATES PATENT OFFICE.

GEORGE W. SMITH, OF MARQUETTE, MICHIGAN, ASSIGNOR OF ONE-HALF TO FREDERICK R. PRESCHER, OF MARQUETTE, MICHIGAN.

AIR-HEATING ATTACHMENT FOR STOVES.

No. 895,052.

Specification of Letters Patent.

Patented Aug. 4, 1908.

Application filed February 6, 1908. Serial No. 414,642.

To all whom it may concern:

Be it known that I, GEORGE W. SMITH, a citizen of the United States, residing at Marquette, in the county of Marquette and State 5 of Michigan, have invented certain new and useful Improvements in Air-Heating Attachments for Stoves; and I do declare the following to be a full, clear, and exact description of the invention, such as will enable 10 others skilled in the art to which it appertains to make and use the same.

This invention relates to improvements in air heating attachments for stoves.

The object of the invention is to provide 15 an attachment of this character adapted to be connected to a stove or stove-pipe whereby the products of combustion may be utilized to increase the heating capacity of the stove.

20 With this and other objects in view, the invention consists of certain novel features of construction, combination and arrangement of parts, as will be more fully described and particularly pointed out in the appended 25 claims.

In the accompanying drawings, Figure 1 is a side view of a portion of a stove showing the application of the attachment thereto, Fig. 2 is an enlarged vertical sectional view 30 through the attachment, and Fig. 3 is a horizontal sectional view of the same.

In the present embodiment of the invention the same is shown as being applied to a stove-pipe and consists of a hollow body portion or drum 1, which is preferably cylindrical in form and constructed of sheet metal. The bottom 2 of the drum is provided with a collar 3, which is adapted to be engaged with the elbow 4, which connects 35 with the stove. The collar 3 is arranged in the bottom 2 adjacent to one side of the cylinder and in the top 5, of the drum adjacent to its opposite side is arranged a collar 6, which is adapted to be connected with the 40 upper portion of the stove-pipe 7, which extends to the chimney 3.

Within the drum 1 are arranged upper and lower baffle plates 8, the lower one of said plates extending over the front side of the 45 drum to near the rear side thereof, thus forming a partition which closes the lower portion of the drum at all points except a small space between the rear edge of the plate and the adjacent rear wall of the drum.

The upper baffle plate 8 is secured to the 55 rear side of the drum and extends across the same to near the forward side thereof and forms a partition which nearly closes the drum above the lower plate, said baffle plates causing the products of combustion which 60 enter the lower end of the drum to pass through the latter in a zigzag manner, said products first passing over the lower side of the drum to the rear side thereof, thence forwardly between the rear edge of the lower 65 baffle plate and the adjacent rear wall of the drum, and thence forward across the drum between the baffle plates, thence upwardly between the forward edge of the plate and the adjacent front side of the drum, after 70 which said products pass rearwardly over the upper plate and out through the stove-pipe connection at the rear portion at the top of the drum.

Arranged on the drum to pass through the 75 same is an air conducting pipe 9, the lower end of which rests on the floor, and is provided with an annular series of air inlet passages 10. The pipe 9 is preferably formed in three sections, the lower section 11 an upper 80 section 12, and an intermediate section 13. The intermediate section 13 is preferably in the form of an oblong box or chamber, which is arranged in the drum midway between the baffle plates 8, as shown, to the lower side of 85 the section 13. Adjacent to its rear end is connected the upper portion of the lower section 11 of the pipe, while to the upper side of the section 13 adjacent to its forward end is connected the lower end of the upper section 90 12 of the pipe. The upper end of the section 12 opens through and is secured to the top of the drum, as shown. The pipe 9 thus forms a flue through which the cold air from the lower portion of the room passes 95 after entering the passages 10, said air being heated in passing through the flue 9 by the heat from the products of combustion, which enter the drum from the stove and are caused to circulate around the pipe or flue 9, by 100 means of the baffle plates 8.

By providing an air heating attachment as herein shown and described the heat from the products of combustion which ordinarily passes out through the stove pipe to the 105 chimney is utilized to assist in heating the air in the apartment or room, thereby providing for a saving of fuel.

Having thus described my invention what I claim as new and desire to secure by Letters-Patent is:—

In an air heating attachment of the character described, the combination with a cylindrical heating drum, of an elliptically shaped heating chamber arranged in said drum midway between its upper and lower ends, an air conducting pipe formed in sections, one of which is connected to the lower side of said chamber adjacent to one end of the same, and extends downwardly through the drum to the floor and the other of which is connected to the upper side of said chamber adjacent to its opposite end, and extends to and opens through the upper end of the

drum, upper and lower baffle plates arranged above and below said chamber to form passages at the opposite ends of the same, thereby providing a circuitous course through the 2 drum, and a smoke pipe connection arranged on each end of the drum, said connections being adjacent to the opposite sides of the drum, substantially as described.

In testimony whereof I have hereunto set 2 my hand in presence of two subscribing witnesses.

GEORGE W. SMITH.
